UNITED STATES PATENT OFFICE.

CHARLES H. BROWN, OF OKLAHOMA, OKLAHOMA.

DESK.

1,192,746.

Specification of Letters Patent. Patented July 25, 1916.

Application filed May 25, 1915. Serial No. 30,272.

To all whom it may concern:

Be it known that I, CHARLES H. BROWN, a citizen of the United States, and a resident of Oklahoma city, in the county of Oklahoma and State of Oklahoma, have invented a new and useful Improvement in Desks, of which the following is a specification.

My invention is an improvement in desks, and the invention has for its object to provide a device of the character specified, more especially adapted for office use, wherein a central support is provided, having a series of horizontal partitions, and mounted on wheels or rollers to permit the support to be moved from place to place and in any direction, and wherein the support is provided with series of shelves at sundry of the partitions extending laterally outward at angles of 90° with respect to each other to permit either shelf to be used independently of all of the others and to permit a number of persons to use the desk simultaneously, and wherein sundry of the shelves are provided with extensions.

In the drawings:—Figure 1 is a perspective view of the improved desk, Fig. 2 is an enlarged section on the line 2—2 of Fig. 1, looking in the direction of the arrows adjacent to the line, Fig. 3 is a perspective view of one of the extensions, Fig. 4 is a vertical section, Fig. 5 is a perspective view of a portion of one of the legs of the support, Fig. 6 is a vertical section through one of the supporting wheels or rollers, and Fig. 7 is a section on the line 7—7 of Fig. 6, looking in the direction of the arrows adjacent to the line.

The present embodiment of the invention comprises a skeleton support, consisting of four legs, posts or pipes, each of which is composed of two integral portions 1 and 1^a, the portions 1 being offset inwardly with respect to the portions 1^a. At the upper end of the portion 1 each pipe is provided with an angular extension 2, and the pipes are arranged with the extensions 2, extending inwardly, and they are connected by a disk 3 of suitable material.

A star-shaped bracket 4 is pivoted to the disk, the said disk having a central opening 5 for receiving pin 6 on the bracket, and a table 7 is secured to the arms of the bracket. The arms of the bracket diverge at angles of 90° with respect to each other,

and they are secured to the under face of the 55 plate or table 7 in any usual or desired manner.

The pipes 1—1^a are connected at the portions 1^a thereof by a frame 8 of metal and of suitable dimensions, the frame being 60 square in the present instance, and being arranged at the inner sides of the pipes as shown. The frame is connected to each pipe or leg by means of a rivet 9 or the like, and the frame holds the legs in proper relation 65 with respect to each other.

Wheels or rollers are connected with the lower ends of the legs, each wheel or roller consisting of two disks 10, connected by a headed pin or rivet 11. This pin or rivet 70 passes through central openings in the disks 10, the said openings being coaxial, and the pin or rivet is headed at the outer face of each disk. The portion of the pin that passes through the central opening of the 75 disk is reduced to limit the inward movement of the wheels or disks.

A standard 12 is secured to each pin or rivet at its center, and each standard is provided at its upper end with a post 13, 80 and with an annular rib 14 between the post and the body of the standard. This post 13 is adapted to engage the lower end of the adjacent pipe and to fit therein, and it will be noted that each pipe is provided 85 at its lower end with a marginal rib 15, resting upon the upper face of the rib 14 and of the same external diameter.

A union in the form of a washer 16 is provided for connecting each standard to the 90 adjacent pipe, each of the said washers 16 having depending pins 17 at its periphery, which engage notches 18 and 19 in the ribs 14 and 15, respectively. The engagement of the pins with the notches prevents angular 95 movement of the bracket and wheels with respect to the post or leg, and the parts are so arranged that the axes of the wheels at diagonally opposite posts or legs will be parallel.

Two bars 20 of angle material are secured to the posts near the lower ends of the portions 1^a thereof. Each bar 20 is connected to two posts, being arranged on the inner sides thereof, and the bars are secured to 105 the posts in any suitable or desired manner. Each bar has a vertical portion which is secured to the post and a horizontal portion

extending inwardly, and a plate or table 21 rests upon the horizontal portion of the bars.

A pair of bars 22 of angle material extends outwardly from each bar 20, the bars 22 being arranged at the inner sides of the posts and at the same level with the bars 20. These bars are arranged with their horizontal portions inwardly, and plates or tables 23 are secured to the portions of the bars by means of screws 24, or the like. The bars 20 extend beyond the support at each end, and similar plates or tables 23 are secured to the horizontal portions of the bars. Thus four of the tables 23 are provided, one plate or table extending outwardly from each of the sides of the plate 21.

It will be noticed from an inspection of Fig. 4, that the plates 23 are of greater thickness than the plate 21, and since the horizontal portions of the bars 20—22 are arranged with their upper surfaces in the same plane the upper surfaces of the plates 23 are above the upper face of the plate 21.

Channel bars 25 are secured to the portions 1 of the posts about half way between the plate or table 7 and the plate or table 21, the said channel bars being parallel with the bars 20, and secured to the pipes at the inner sides thereof. The channel bars 25 are arranged with their channels inwardly, and other pairs of channel bars 26 are arranged parallel with the bars 22. Each pair of channel bars 26 is parallel to the adjacent pair of bars 22, and these bars 26 are arranged with respect to the bars 25 in the same manner as are the bars 22 with respect to the bars 20.

A plate 21^a is supported on the upper flanges of the channel bars 25, the said plate being square and similar to the plate 21, before mentioned. Other plates or tables 23^a similar in all respects to the plate 23, are arranged on the extended ends of the channel bars 25 and on the channel bars 26. The plates 23^a are secured to the upper flanges of the channel bars 25 and 26, by means of screws 27 or the like.

A plate or slide 28 is mounted in the channels of each pair of channel bars 26 and in the channels at each end of the bars 25, the slide bars being of a length to extend from the outer ends of the plates 23^a to the adjacent pair of pipes 1 and 1^a, when the extensions are in inward position.

Each extension is provided with a handle in the form of a loop or bail on its under side, each loop or bail comprising a body 29 and arms 30, secured to the under face of the plate. A second handle or support is connected to each slide plate at the outer end thereof, each of the said handles or supports comprising a body 31 and arms 32, extending laterally from the ends of the body.

Each arm 32 is provided with a lateral

lug 33 at the end remote from the body, and extending at right angles to the arm, and these lugs are secured to the under face of the plate in any suitable manner outside the ends of the handle 29—30. The handles 31—32—33 are so arranged that the bodies of the bails will be above the table 23^a and at the outer end thereof, while the handle 29—30 is so arranged that the body thereof will be below the plate 23^a and spaced downwardly therefrom.

The outer ends of the bars 26 and the outer ends of the bars 25 are braced against the pipes by inclined braces 34. The said braces are ornamental in form, and each brace is secured at one end to the outer face of the adjacent bar and at the other end to the adjacent pipe or leg.

The improved desk requires but little floor surface, and since each of the extensions is spaced apart from all of the other extensions any extension is easily accessible, and may be used independently of the others. The several extensions or shelves may be extended by pulling out the adjacent slide, this making each shelf of the upper series about twice the usual length.

The improved desk is not liable to tip over, because of the broad base. The plates 7—21—21^a may be used for storage, while the shelves proper may be used for work or for storage. For office use, the desks are very convenient for books. The book will rest with the back on the extension, the extension being pulled out to receive the book, and with one back or cover resting on the handle 31 and the other on the plate 23^a adjacent thereto. The books may be stored on the shelves 23 and lifted into a position of use on to the upper shelves.

The plates 21 are especially suitable for holding ink stands, pens, pencils, and the like. Whenever it is desired to move the table the locking rings 16—17 may be lifted upward to release the ribs 14 and 15 from each other. When so released the rollers are casters. When the locking rings are dropped however, the wheels are locked, locking the support against movement in any direction.

It is obvious that with the wheels locked, they cannot roll freely in any direction. When released however, all may take a position with their axes parallel to permit the free rolling of the support.

I claim:—

1. A desk embodying a support comprising parallel connected legs, a plurality of series of pairs of bars connected with the support, the bars of each series having their upper surfaces in the same plane, and the members of each pair extending in parallel relation from one side of the support, a table secured to the bars of each pair of each series, the bars of the upper series be-

ing channel bars and having their channels inwardly, an extension plate mounted to slide in the channels between each pair of bars, each plate having a depending handle 5 and a handle extending above the adjacent table, said last-named handle having a portion parallel with the upper surface of the table and extending transversely thereof.

2. A desk embodying a support comprising parallel connected legs, a plurality of series of pairs of bars connected with the support, the bars of each series having their upper surfaces in the same plane, and the members of each pair extending in parallel 10 relation from one side of the support, a table secured to the bars of each pair of each series, the bars of the upper series being channel bars and having their channels inwardly, and an extension plate mounted to 15 slide in the channels between each pair of bars.

3. A desk consisting of a support composed of spaced connected legs arranged at angular intervals of 90° about a common 20 center, a pair of approximately parallel channel bars extending laterally outward from each side of the support and connected with the legs, the channels of each pair of bars being inward, a table secured to the 25 top of each pair of bars, and an extension mounted to slide in the channels of each pair of bars, each plate having a depending handle, and a handle extending above the adjacent table and provided with a portion parallel 30 with the table and extending transversely thereof.

35

4. A desk consisting of a support composed of spaced connected legs arranged at angular intervals of 90° about a common center, a pair of approximately parallel 40 channel bars extending laterally outward from each side of the support and connected with the legs, the channels of each pair of bars being inward, a table secured to the top of each pair of bars, and an extension 45 mounted to slide in the channels of each pair of bars.

5. A desk comprising a support embodying transversely connected legs, bars extending outwardly from the legs of the support, 50 tables carried by said bars, and plates slidably mounted upon the bars and mounted beneath the tables.

6. A desk comprising a support having legs, bars attached to the legs and forming 55 connecting means therefor and projecting outwardly beyond the legs, tables attached to the projecting ends of the bars, and slides mounted to slide in the bars below sundry of the tables.

7. A desk comprising a support embodying legs, bars extending between and connecting the said legs and projecting outwardly therefrom, plates secured to the bars between the legs, tables attached to the outer 60 ends of the bars, and slides mounted upon the bars beneath the tables.
